UNITED STATES PATENT OFFICE.

MICAJAH L. POULTER AND MARION J. MUNSON, OF STOCKPORT, IOWA.

TILE-DITCHING MACHINE.

No. 868,937.

Specification of Letters Patent.

Patented Oct. 22, 1907.

Application filed October 8, 1906. Serial No. 337,877.

To all whom it may concern:

Be it known that we, MICAJAH L. POULTER and MARION J. MUNSON, citizens of the United States, residing at Stockport, in the county of Van Buren and 5 State of Iowa, have invented a new and useful Improvement in Tile-Ditching Machines.

The following specification contains a full, clear, and exact description of our invention.

This invention relates to an improvement in ditching 10 machines, and particularly to a tile ditching machine.

The object of the invention is the provision of means for facilitating the cutting of a straight ditch or trench, elevating the dirt therefrom to the surface of the ground, 15 and depositing the same a sufficient distance from the excavation to prevent it from falling back therein.

With this and other objects in view, the invention consists of certain novel constructions, combinations, and arrangements of parts, as will be hereinafter fully 20 described and claimed.

In the drawings: Figure 1 is a view, in side elevation, of a mechanism constructed in accordance with our invention. Fig. 2 is a top plan view of the mechanism depicted in Fig. 1. Fig. 3 is a transverse sectional view taken on line *a*, *a*, Fig. 1, and looking in the direction of the arrow. Fig. 4 is a fragmentary view in side elevation of the lifting cables and winding drum of the excavating device, and Fig. 4^a is a front view of the same. Fig. 5 is a perspective view of the 25 scraper for cleaning the scoops or shovels. Fig. 6 is a fragmentary, perspective view of the framework, conveyer, and excavating-device. Fig. 7 is a top plan view of one of the scoops or shovels and showing a portion of the excavator-frame in horizontal section. Fig. 30 8 is a view in side elevation of one of the links of the excavator-chain, while Fig. 9 is an end view, in elevation, of the same. Fig. 10 is a rear view, in elevation, of one of the scoops or shovels and showing the excavator-chain attached thereto, and Fig. 11 is a 35 similar view, looking at the scoop or shovel at right-angles to Fig. 10. Fig. 12 is a fragmentary top plan view of a portion of the driving means for the excavator-device, while Fig. 13 is a view of the same in side elevation. Fig. 14 is a perspective view of the marker-40 stakes. Fig. 15 is a top plan view of the level-device, and Fig. 16 is a view in side elevation of the same. Fig. 17 is a fragmentary view, in elevation, of the excavating device, showing particularly the framework and the gearing thereof, while Fig. 18 is a vertical sectional view taken on line 18, 18, Fig. 17 of the same. Fig. 19 is a horizontal, sectional view on line 19, 19, Fig. 18 and looking in the direction of the arrow. Fig. 20 is a fragmentary view in side elevation of the excavating-device, showing particularly the shovels or 45 scoops and the endless chain-carrier therefor. Fig. 21 is a fragmentary plan view of the clutch device em-

ployed in actuating the means for raising and lowering the vertically-adjustable excavating-device, while Fig. 22 is a view in elevation of the same.

Referring to the drawings, 30 designates the base or 60 platform of the framework, which is supported upon front and rear axles 31 and 32. Journaled upon the front and rear axles 31 and 32, respectively, are wheels 33 and 34 respectively. The front axle 31 is pivotally connected to king-bolt 35. Mounted upon the frame- 65 work 30 is an engine 36, by means of which power is derived for propelling the machine over the ground, and for driving the excavating-device and conveyer, as hereinafter described.

The guiding device for the front wheels 33 comprises 70 a chain 37, suitably wound or connected upon shaft 38 and having its outer ends fixedly secured to the front axle 31. The worm-gear device 39 is operably connected in any ordinary manner to shaft 38, and said worm-gear device is actuated through the medium of 75 inclined shaft 40 by a hand-wheel 41, which wheel 41 is mounted upon the machine near the rear thereof, whereby the operator of the mechanism can easily control the direction of travel of the entire machine, when the same is passing over the ground. 80

It will be obvious that upon rotating shaft 40, movement will be imparted to the shaft 38, through the medium of the worm-gear device 39, and, consequently, the sections of the chain 37 will be moved and will swing the shaft 31 upon the king-bolt 35 in the direc- 85 tion it is desired that the machine should travel.

Sprocket-chain 42 is suitably connected to the engine 36, and said sprocket-chain passes around one sprocket-wheel of a train of meshing sprocket-wheels 43, which particular wheel is fixedly secured to shaft 43^a. 90 Sprocket-wheel 43^b of said train is fixedly secured to a rotatable shaft 43^c, which shaft carries, near its ends, pinions 43^d that mesh with large gear-wheels or annular racks 43^e, fixedly secured to the rear wheels 34. A rod 44 is mounted upon the framework 30, and said rod is 95 connected, at one end, with any ordinary clutch-device 44^a, cooperating with the engine, and at its opposite end, with a lever 45. Through the medium of this rod 44, clutch-device 44^a, and lever 45, the gearing for driving the machine over the ground may be thrown in or 100 out of operation.

The excavating-device 46 comprises a frame having parallel sides 46'. Each of the sides 46' comprises a metallic frame having an endless groove 46^a, for the purpose hereinafter described. The frame 46 is slid- 105 ably mounted in vertical, slotted, or grooved standards 47, which standards 47 are fixedly secured to framework 30. Journaled in the upper ends of the standards 47 is a horizontal drum or shaft 48, to which is secured, at one of their ends, cables 49. The cables 49 are se- 110 cured at their lower ends to the sides 46' of the frame of the excavating-device 46. Fixed to the drum or

shaft 48 and preferably near one end thereof, is a sprocket-wheel 50. Upon the sprocket-wheel 50, there is positioned a sprocket-chain 48^a, which sprocket-chain also passes around a sprocket-wheel 51, that is 5 fixedly secured to shaft 48^b. A pinion 51^c, fixed to shaft 48^b, meshes with a worm-wheel 52 carried by shaft 48^c, see Fig. 1. Secured to the rear end of shaft 48^c (see Figs. 1 and 21) is a beveled gear 48^d, which gear is adapted to mesh with beveled gears 48^e, fixed to shaft 10 48^f. By shifting the shaft 48^f, by any suitable means, the direction of rotation of beveled gear 48^d will be changed, and, therefore, the direction of travel of the endless sprocket-chain 48^a, which imparts motion to the winding drum or shaft 48. It will, therefore, be ob-15 vious that, as the excavating-device 46 moves in a vertical plane between the uprights or standards 47, the bodily-movement of said excavating-device can be changed through the medium of the clutch-device. A hand-wheel 54 is secured to the front end of shaft 48^c. 20 By rotating the hand-wheel 54, the excavating-device can be manually elevated and lowered. If it is desired, the excavating-device can be elevated and lowered through the medium of the engine 36.

The elevating and lowering of the excavating-device 25 46 is accomplished through the medium of the engine 36 by means of a sprocket-chain 54^a, passing over gears 54^b and 79', Fig. 1, which gear 54^b is secured to shaft 48^f, see Fig. 3. It will, therefore, be noted that we have not only provided manually operated 30 means for elevating and lowering the excavating-device, but also means actuated directly by the engine for accomplishing these results.

Before the machine is placed in operation, it is desirable that the same should be correctly positioned 35 for cutting the ditch, and, therefore, we employ a level device, which comprises a weighted arm 55 pivotally secured at 55' to a horizontal bracket 55^a that is integral with a vertical flange or portion 55^b, which portion 55^b is secured to the excavating-device. The horizontal arm 56 is pivoted to the bracket, as at 56', and said arm 56 is provided with a vertical, integral extension that is connected preferably at its upper end to the upper end of the arm 55, through the medium of a link 55^c. By means of the weighted arm 55, the horizontal 40 arm 56 will, at all times, be retained in a correct, horizontal position. Stakes, which are driven at pre-determined distances apart into the ground, along the line to be excavated, comprise vertically adjustable sections 59 carried by uprights 61, which uprights are connected to said adjustable section through the medium of a clamp and thumb-screw device 58.

As the level-device is carried by the excavating device, the operator, sitting in seat 60, can easily raise or lower the excavating-device, as hereinbefore 55 described, so that, although the machine is traveling over uneven ground, the arm 54 can be retained in alignment with the horizontal arms of the vertically adjustable sections of the marker-stakes. As before stated, the frame of the excavating-device, carrying 60 the level-device, comprises the sides 46', upon which is suitably journaled sprocket-wheels 67, around which wheels, the endless carrier-chain 62 passes. Coöperating with the carrier or sprocket-chain 62, carrying bucket-like scoops or shovels 68, hereinafter described, is a horizontal, endless conveyer 64, which is

adapted to receive and convey the dirt or excavated material from the scoop to one side of the machine. This conveyer 64 is provided with slots or openings, through which the bucket-like scoops or shovels 68 pass. The conveyer works intermittently, or, in other words, does not move when the chain-carrier 62 is in motion. After each scoop has passed above the conveyer 64, Figs. 6 and 20, the conveyer 64 is moved a slight distance, by any suitable means, so as to place the solid portion of the same under the scoop which has just passed above said conveyer for receiving the load from the scoop. 70 75

Secured to a horizontal shaft 66^b, journaled in the upper end of the excavating-device frame 46, is a pinion 66, which meshes with a pinion 66^a. The pinion 66^a is fixed to shaft 66^c, to which shaft 66^c is fixed a belt-wheel 78, see Figs. 1, 3 and 13. The belt-wheel 78 is connected to a wheel 79 of the engine 36, through the medium of an endless belt 77, which belt 77 passes over wheels 80, 81, and 82, carried by the frame. 80 Fixed to the shaft 66^b and within the excavating-device frame is a sprocket-wheel 66^d, and suitably journaled in the lower end of said frame is another sprocket-wheel 67. The sprocket-chain or carrier 62 passes around these sprocket-wheels 66^d and 67. 90

Each of the bucket-like scoops or shovels 68 comprises a body provided with open ends and with a longitudinally-extending opening or slot 76 upon its outer side. The upper end of the scoop is preferably sharpened to facilitate its cutting or digging in the earth. 95 Secured to a portion 30^a of the framework, is a scraper 74, preferably cylindrical-shape, and composed of sections, which sections are preferably secured together, at 75, and having their inner ends suitably attached to said portion 30^a of the framework. The scraper is in the path of movement of the scoops or shovels 68, and as each scoop passes upward, the scraper 74 will pass through the scoop or shovel and clean the same of all of the dirt or load contained therein. The scraper is preferably sharpened at its lower end, and of necessity, moves in the slotted portion 76 of each scoop. Each scoop 68 is secured, through the medium of lugs 69, to links 62^c of the endless carrier or sprocket-chain 62. The links 62^c are provided with horizontally-extending shafts 62^a, upon which are journaled wheels 100 105 110 115 120 125 130

83. These wheels 83 travel in the slots or guide-ways 46^a of the excavating-device frame. Each of the slots 46^a are formed by a pair of angle-irons bent so as to produce an endless track or slot. It will, therefore, be noted that each scoop or shovel is provided preferably with a pair of lugs 69, and these lugs are integral with links 62^c of the sprocket-chain or carrier 62. Each link 62^c is provided with a pair of wheels working in guide-ways of the excavating-device frame. The bottom 70 of the scoop is pivoted, as at 70', upon the lower lug 69'. A bell-crank lever 70^a is pivotally mounted upon one of the lower shafts 62^a of a link 62^c, and said lever 70^a is connected to the hinged bottom 70, through the medium of a link 70^b. A stub-shaft 70^c is secured to lever 70^a and journaled upon said stub-shaft is a wheel 71. The wheel 71 is adapted to engage the track 73, which is secured between the sides 46' of the excavating device. During the downward run of each scoop 68, the wheel 71 will come in contact with the end 73^a of track 73, (Fig. 20) and as said wheel passes over the

- outwardly curved portion 73^b, the bottom 70 of the scoop will be closed and retain the dirt or load within said scoop until the wheel 71 has passed the upper end 73^c of said track, when the bottom 70 will swing down-
 5 ward and permit the load to be deposited upon the conveyer 64. It will, therefore, be noted that we have provided link and lever means actuated by a wheel passing over a track for holding the bottom in a closed position upon the scoop. Furthermore, while the load
 10 in the scoop will have a tendency of dropping out of the same, when the bottom 70 is released, still the scraper 74 will positively remove the load from within the scoop besides cleaning the same, which will materially facilitate the operation of the excavating device,
 15 as the scoop will not be clogged.
- Secured to one end of shaft 66^b is a beveled gear 66^e, meshing with a beveled gear 66^f, which gear 66^f is fixed to shaft 66^g, see Fig. 1. A sprocket-wheel 66^h is fixed to the outer end of shaft 66^g, and a chain 66ⁱ
 20 passes over said wheel 66^h. The chain 66ⁱ also passes over a sprocket-wheel 66^k (see Fig. 3), which wheel 66^k is connected to the conveyer 64.
- What we claim is:
1. In a ditching machine, the combination with a frame-
 25 work, an endless-carrier supported upon said framework, of a scoop secured to said carrier, stationary means for cleaning the entire inside of said scoop, and means for driving said carrier.
  2. In a ditching machine, the combination with a frame-
 30 work, a carrier positioned upon said framework, of a scoop secured to said carrier, a scraper secured to said framework and adapted to pass through said scoop for cleaning the inside of the same, and means for driving said carrier.
  3. In a ditching machine, the combination with a frame-
 35 work, a carrier supported upon said framework, of a scoop secured to said carrier, said scoop provided with a slot formed in its side and extending its entire length and said slot open at both ends, and means carried by said framework and adapted to be positioned within the slot of said
 40 scoop for cleaning the inside thereof, and means for driving said carrier.
  4. In a ditching machine, the combination with a frame-
 work, a carrier supported thereby, of a scoop secured to said carrier, said scoop provided with open ends and a
 45 slotted side, a scraper secured to said framework and adapted to extend through the slot of said side and into said scoop, means for closing one end of said scoop, and means for driving said carrier.
  5. In a ditching machine, the combination with a frame-
 50 work, a carrier supported upon said framework, of a scoop provided with an elongated opening upon one side, secured to said carrier, means working in said opening for cleaning the inside of said scoop, and means for imparting motion to said carrier.
  6. In a ditching machine, the combination with a frame-
 55 work, a carrier supported upon said framework, of a scoop secured to said carrier, a sectional scraper secured to said framework and adapted to be positioned in said scoop as the same passes said scraper, and means for imparting motion to said carrier.
  7. In a ditching machine, the combination with a frame-
 60 work, a carrier supported upon said framework, of a scoop secured to said carrier, a scraper comprising sections, each section secured at one end to said framework and having its outer end left free, said scraper adapted to be positioned within said scoop for cleaning the same as said scoop in its travel passes the scraper, and means for imparting motion to said carrier.
  8. In a ditching machine, the combination with a frame-
 65 work, a carrier supported upon said framework, of a scoop secured to said carrier, a scraper secured to said framework in the path of movement of said scoop and adapted to be positioned in the scoop and scrape its entire length for cleaning the same, and means for driving said carrier.
  9. In a ditching machine, the combination with a frame-
 70 work, a carrier supported upon said framework, of a scoop secured to said carrier, a scraper secured to said framework comprising links, wheels journaled upon the opposite sides of some of said links and traveling in the grooves of the sides of the framework, a scoop secured to said carrier, and means for driving said carrier.
  10. In a ditching machine, the combination with a frame-
 75 work, a carrier supported upon said framework, of a scoop provided with a movable bottom, secured to said carrier, lever and link means connected to said bottom, means for driving said carrier, and means for actuating said lever and link means during a portion of the travel of the carrier for holding the bottom in a closed position.
  11. In a ditching machine, the combination with a frame-
 80 work, a carrier supported upon said framework, of an open-ended scoop secured to said carrier, a movable cover or bottom for closing one end of said scoop, lever and link means coöperating with said bottom for holding the same in a closed position during a portion of the travel of the scoop, and means for imparting movement to said carrier.
  12. In a ditching machine, the combination with a frame-
 85 work, an endless carrier supported upon said framework, of a scoop secured to said carrier, said scoop provided with a hinged bottom, a lever pivotally mounted upon said carrier, means connecting said lever to said bottom, a track, means connected to said lever and passing over said track for holding said bottom in a closed position, and means for driving said carrier.
  13. In a ditching machine, the combination with a frame-
 90 work, a carrier supported upon said framework, of a scoop provided with a movable bottom and secured to said carrier, of a bell-crank lever secured to said carrier, means connecting said lever to said bottom, and means for moving said lever for actuating said bottom.
  14. In a ditching machine, the combination with a frame-
 95 work, a carrier supported upon said framework, of a scoop provided with a hinged bottom secured to said carrier, a bell-crank lever connected to said carrier, a link, means for moving said lever and link for closing said bottom and holding it in said position, and means for driving said carrier.
  15. In a ditching machine, the combination with a frame-
 100 work, a carrier supported upon said framework, of a scoop secured to said carrier, said scoop provided with a hinged bottom, a bell-crank lever pivotally mounted upon said carrier, means connecting said lever to said bottom, a stub-shaft secured to said lever, a wheel journaled upon said stub-shaft, a track, said wheel adapted to pass over said track for holding said bottom in a closed position, and means for driving said carrier.
  16. In a ditching machine, the combination with a frame-
 105 work, of an endless-carrier positioned upon said framework, an open-ended scoop secured to said carrier, said scoop provided with a hinged bottom for closing one end thereof, a bell-crank lever pivotally mounted upon said carrier, a wheel journaled upon said lever, means connecting one end of said lever to said bottom, a track, said wheel adapted to pass over said track for swinging and retaining said bottom in a closed position during a portion only of the travel of said scoop, and means for driving said carrier.
  17. In a ditching machine, the combination with a frame-
 110 work, of an excavating-device carried by said framework, said excavating-device comprising a framework consisting of sides provided with endless grooves, a carrier working between said sides, said carrier comprising links, wheels journaled upon some of said links and traveling in the grooves of the sides of the framework, a scoop secured to said carrier, and means for driving said carrier.
  18. In a ditching machine, the combination with a frame-
 115 work, of a vertically-adjustable excavating-device carried by said framework, said excavating-device comprising a framework consisting of sides provided with endless grooves, a carrier working between said sides, said carrier comprising links, wheels journaled upon the opposite sides of some of said links and traveling in the grooves of the sides of the framework, a scoop secured to said carrier, and means for driving said carrier.
  19. In a ditching machine, the combination with a frame-
 120 work, of an excavating-device carried by said framework, said excavating-device comprising a framework consisting of sides provided with endless grooves, a carrier working between said sides, said carrier comprising links, wheels journaled upon the opposite sides of some of said links and traveling in the grooves of the sides of the framework, a scoop secured to said carrier, and means for driving said carrier.
  20. In a ditching machine, the combination with a frame-
 125 work, of an excavating-device carried by said framework, said excavating-device comprising a framework consisting of sides provided with endless grooves, a carrier working between said sides, said carrier comprising links, wheels journaled upon the opposite sides of some of said links and traveling in the grooves of the sides of the framework, a scoop secured to said carrier, and means for driving said carrier.
  21. In a ditching machine, the combination with a frame-
 130 work, of an excavating-device carried by said framework, said excavating-device comprising a framework consisting of sides provided with endless grooves, a carrier working between said sides, said carrier comprising links, wheels journaled upon the opposite sides of some of said links and traveling in the grooves of the sides of the framework, a scoop secured to said carrier, and means for driving said carrier.
  22. In a ditching machine, the combination with a frame-
 135 work, of an excavating-device carried by said framework, said excavating-device comprising a framework consisting of sides provided with endless grooves, a carrier working between said sides, said carrier comprising links, wheels journaled upon the opposite sides of some of said links and traveling in the grooves of the sides of the framework, a scoop secured to said carrier, and means for driving said carrier.
  23. In a ditching machine, the combination with a frame-
 140 work, of an excavating-device carried by said framework, said excavating-device comprising a framework consisting of sides provided with endless grooves, a carrier working between said sides, said carrier comprising links, wheels journaled upon the opposite sides of some of said links and traveling in the grooves of the sides of the framework, a scoop secured to said carrier, and means for driving said carrier.
  24. In a ditching machine, the combination with a frame-
 145 work, of an excavating-device carried by said framework, said excavating-device comprising a framework consisting of sides provided with endless grooves, a carrier working between said sides, said carrier comprising links, wheels journaled upon the opposite sides of some of said links and traveling in the grooves of the sides of the framework, a scoop secured to said carrier, and means for driving said carrier.
  25. In a ditching machine, the combination with a frame-
 150 work, of an excavating-device carried by said framework, said excavating-device comprising a framework consisting of sides provided with endless grooves, a carrier working between said sides, said carrier comprising links, wheels journaled upon the opposite sides of some of said links and traveling in the grooves of the sides of the framework, a scoop secured to said carrier, and means for driving said carrier.

19. In a ditching machine, the combination with a framework, of a vertical, endless-carrier supported upon said framework, a scoop secured to said carrier, a horizontal conveyer positioned contiguous to and in the path 5 of movement of said scoop, said conveyer provided with an opening through which said scoop is adapted to pass in its travel, and means for driving said carrier and conveyer in timed relation. 70
20. In a ditching machine, the combination with a framework, of an excavating-device provided with a scoop, carried by said framework, a conveyer in the path of movement of said scoop, said conveyer provided with an opening through which the scoop is adapted to pass in its upward travel, and means for actuating said conveyer and 10 carrier in timed relation. 75
21. In a ditching machine, the combination with a framework, of a carrier, a conveyer coöperating therewith, said carrier provided with a scoop adapted to pass through said conveyer, and means for actuating said carrier and conveyer in timed relation. 80
22. In a ditching machine, the combination of a carrier, a conveyer coöperating therewith, a scoop secured to said carrier and adapted to pass through said conveyer, said scoop provided with a hinged bottom, means holding said bottom in a closed position upon said scoop as the same passes through said conveyer and adapted to release the bottom for permitting a load in the scoop to be deposited upon said conveyer when the scoop is above the same, and means for imparting motion to said carrier and conveyer. 85
23. In a ditching machine, the combination of a carrier and a conveyer, a scoop secured to said carrier and adapted in its travel to be positioned above said conveyer, said scoop provided with a movable bottom, means for closing the bottom during a portion of the travel of the carrier 30 and holding the bottom in said closed position until the scoop is positioned above said conveyer, and means for imparting movement to said carrier and conveyer. 90
24. In a ditching machine, the combination with a framework, of a vertical carrier supported by said framework, a horizontal conveyer supported by said framework, said conveyer positioned contiguous to said carrier, load-receiving and supporting means attached to said carrier and adapted to pass through said conveyer and deposit a load upon the upper run of the same, and means for actuating said conveyer and carrier in timed relation. 95
25. In a ditching machine, the combination with a framework, of a carrier supported upon said framework, a conveyer supported by said framework and contiguous to said carrier, load-receiving and supporting means attached to said carrier and adapted to pass through said conveyer and deposit a load upon the same, and means for actuating said conveyer and carrier in timed relation. 100
26. In a ditching machine, the combination with a framework, of standards secured to said framework, a rotatable drum or shaft journaled upon said standards, an adjustable excavating-device positioned between said standards, cables secured upon opposite sides of said excavating-device and connected to and adapted to be wound upon said drum for adjusting said device, and means for imparting rotary movement to said drum. 105
27. In a ditching machine, the combination with a framework, of a drum carried by said framework, an excavating device, pairs of cables positioned upon opposite sides and secured to said excavating-device, said cables 110 connected to and adapted to be wound upon said drum for adjusting said excavating-device, and means for rotating said drum. 115
28. In a ditching machine, the combination of stand- 120 ards, a vertically-adjustable excavating-device positioned between said standards, a winch connected to said standards and to the upper end of said excavating-device for adjusting said device, and means for actuating said winch for adjusting said excavating-device. 125
29. In a ditching machine, the combination of stand- 125 ards, a vertically-adjustable excavating-device positioned between said standards, a winch connected to said standards and to said excavating-device for adjusting said device, a clutch-device, means connecting said clutch-device to said winch, and means for actuating said clutch-device for controlling movement of said winch and the vertical adjustment of said excavating-device. 130
30. In a ditching machine, the combination with a framework, of a vertically-adjustable excavating-device carried by said framework, a level-device connected to said excavating-device, said level-device comprising a bracket, a pivotally-mounted vertical arm carried by said bracket, a pivotally-mounted horizontal arm carried by said bracket, and means connecting said horizontal and vertical arms. 135
31. In a ditching machine, the combination with an excavating-device, or a level-device secured to said excavating-device, said level-device comprising a bracket, a pivotally-mounted, weighted arm carried by said bracket, a pivotally-mounted horizontal arm carried by said bracket, and a link connecting said arms. 140
32. In a ditching machine, the combination with a framework, of a level-device supported upon said framework, said level-device comprising a bracket provided with a horizontal extension, a weighted, vertical arm pivotally mounted upon said extension, a horizontal arm provided with a vertical extension, pivotally mounted upon said bracket, means connecting the extension of the horizontal arm and the upper end of said weighted arm, and a stake, said stake provided with an adjustable extension coöperating with the horizontal arm of said level-device. 145
33. In a ditching machine, the combination with a framework, of a level-device carried thereby, said device comprising a horizontal pivotally-mounted arm, a weighted-member, means connecting said weighted member to said arm, whereby said arm is normally retained in a horizontal position. 150
34. In a ditching machine, the combination with a framework, of a level-device supported upon said framework, said device comprising a horizontal pivotally-mounted arm, a weighted-member, means connecting said weighted member to said arm, whereby said arm is normally retained in a horizontal position. 155
35. In a ditching machine, the combination with a framework, of a vertically adjustable excavating-device carried by said framework, a gear-wheel journaled upon said framework, means connecting said gear-wheel to said excavating-device, whereby when said wheel is rotated, vertical movement will be imparted to said excavating-device, a worm meshing with said gear-wheel, means for reversing the direction of rotation of said worm and thereby the vertical adjustment of said excavating-device. 160

In testimony whereof we have signed this specification in the presence of two witnesses.

MICAJAH L. POULTER.
MARION J. MUNSON.

Witnesses:

F. M. MATHEWS,
SAMUEL M. WHITMER.
